Atty.

UNITED STATES PATENT OFFICE

WILHELM LUDOWICI, OF MUNICH, GERMANY

SELF-DISCHARGING WAGON

Application filed August 24, 1929, Serial No. 388,163, and in Germany December 20, 1927.

My invention refers to self-discharging wagons and more especially to cars having oscillatable side walls and a movable bottom. It is an object of my invention to provide a car of the kind which is simpler in construction and more efficient in operation than similar cars hitherto designed.

In the car according to this invention the end walls are fixed on the wheeled frame. 10 The side walls are pivotally suspended from the end walls so as to be capable of rocking about pivots arranged near their top edges. The bottom is loosely inserted between the end walls and supported solely by a shaft 15 extending longitudinally of the car and supported in bearings fixed to or forming part of the end walls. On the bottom being slightly shifted towards one or the other side, the load acting on the bottom will cause it to 20 glide on the shaft and to assume an oblique discharging position.

In the preferred form of the new car the bottom edges of the side walls are pivotally connected by links with the bottom preferably in 25 the longitudinal middle line thereof and on the bottom being displaced sideways will be rocked about their pivots, the side wall on the side, towards which the bottom is sliding, being lifted upwardly, while the other side 30 wall is forced by the links to follow the movements of the adjoining edge of the bottom.

In the drawings affixed to this specification and forming part thereof, a car embodying my invention is illustrated diagrammatically 35 by way of example.

In the drawings

Fig. 1 is a side elevation and

Fig. 2 is an end elevation of the car, while Fig. 3 is a cross-section.

40 Referring to the drawings, 1 is the wheeled underframe and 2 are the end walls fixed thereon. 3 is the movable bottom and 4 is the shaft supported in bearings provided in the end walls and 5 are toothed wheels mounted on said shaft near the ends thereof and meshing with racks 6 fixed to the underside of the bottom. 7 is another shaft extending at right angles to shaft 3 and fitting in bearings 8 fixed on the outside of one of the end walls. 45 9 is a cog wheel fixed on shaft 7 and meshing

with another cog wheel 10 on the end of shaft 4, which projects through the end wall adjoining shaft 7. By means of a crank 11 fixed to shaft 7 the wheels 9, 10 and shaft 4 can be rotated, whereby the bottom plate 3 55 will be displaced towards one or the other side and will be depressed on the side, towards which it has been displaced, by the load acting thereon.

Pins 12 mounted on the edges of the bottom plate adjoining the end walls project through curved slots 13 provided in these end walls, and form pivots for links 14 hinged at 15 to the bottom ends of the side walls 16, which are suspended from the end walls by means of hinge pins 17. 18 are checks provided on the end walls and limiting the rocking movements of the side walls 16. 19 are curved slots extending from the outer edges of the end walls towards the middle thereof and allowing the pivot pins 15 to enter these walls, when one of the side walls is swinging inwardly.

The operation of this car is illustrated in Fig. 3. By rotating the crank shaft 7, the 75 shaft 4 supporting the bottom is rotated in the opposite direction and the bottom plate 3 has thus been displaced towards the left on the drawings, whereby the equilibrium of the plate has been disturbed so that with or without the assistance of the load resting on the plate its left hand portion will drop and the plate will assume an oblique position as shown on the drawings. At the same time the pins 12 fixed to the bottom plate will 80 push the side wall on the left hand side open by means of the links or rods 14 connecting the pins 12 with the side wall, while the side wall 16 on the right hand side is pulled into the car body by the corresponding rod 90 or rods 14 connecting same with the pins 12. In the position of the parts shown in the drawings the bottom edge of the side wall 16 has followed the movement of the adjoining lateral edge of the bottom plate. 95

Instead of being pivoted to the same pivot pin 12, the rods or links 14 covering the side walls may be pivoted to separate pins positioned at different points of the bottom plate and in this case the width of the gap 100

forming between the side wall and the bottom plate may be regulated at will. While in the modification illustrated in the drawings the link rods 14 are arranged outside of the wagon body, they might also be arranged within same and in that case the slots 13 and 19 might be dispensed with. Alternatively, these links might also be bent so as to avoid the necessity of providing slots 19.

- 10 In order to be able to discharge several wagons of a train of wagons at a time, the shafts 4 of adjoining wagons may be provided with coupling means, which may be of a pneumatic or electric kind so that by displacing one of the shafts the bottom plates of all the wagons will be displaced simultaneously.
- 15 Various changes may be made in the details disclosed in the foregoing specification, without departing from the invention or 20 sacrificing the advantages thereof.

I claim:

1. Self-discharging wagon comprising two fixed end walls, a shaft having its ends supported in said walls, a bottom supported by 25 said shaft and parallelly displaceable thereon, side walls pivotally suspended from said end walls and links pivotally connecting said side walls with the edges of said bottom which adjoin said end walls.
30. 2. Self-discharging wagon comprising two fixed end walls, a shaft having its ends supported in said walls, a bottom supported by said shaft and parallelly displaceable thereon, side walls pivotally suspended from said end walls and links pivotally connecting the bottom ends of said side walls with the edges of said bottom which adjoin said end walls.
35. 3. Self-discharging wagon comprising two fixed end walls, a shaft having its ends supported in said walls, a bottom supported by said shaft and parallelly displaceable thereon, side walls pivotally suspended from said end walls and links pivotally connecting said side walls with the middle portion of the edges of said bottom which adjoin said end walls.
40. 4. Self-discharging wagon comprising two fixed end walls, a shaft having its ends supported in said walls, a bottom supported by said shaft and parallelly displaceable thereon, side walls pivotally suspended from said end walls and links pivotally connecting said side walls with the middle portion of the edges of said bottom which adjoin said end walls.
45. 5. Self-discharging wagon comprising two fixed end walls, a shaft having its ends supported in said walls, a bottom supported by said shaft and parallelly displaceable thereon, side walls pivotally suspended from said end walls and links pivotally connecting said side walls with the middle portion of the

edges of said bottom which adjoin said end walls, said links extending along the outer sides of said end walls and being connected with said bottom across slots in said end walls, said end walls being further provided with curved slots, open at one end.

70 In testimony whereof I affix my signature.

WILHELM LUDOWICI.
